UNITED STATES PATENT OFFICE

164,595

TENDON PROTECTOR OR SIMILAR ARTICLE

George Owen, Jr., Milton, and Jerome A. Rubico,
East Boston, Mass.

Application January 18, 1949, Serial No. 288

Term of patent 3½ years

(Cl. D7—7)

To all whom it may concern:

Be it known that we, George Owen, Jr., a citizen of the United States, and a resident of Milton, county of Norfolk, and State of Massachusetts, and Jerome A. Rubico, a citizen of the United States, and a resident of East Boston, county of Suffolk, and State of Massachusetts, have jointly invented a new, original, and ornamental Design for a Tendon Protector or Similar Article, of which the following is a specification, reference being made to the accompanying drawing forming part thereof.

In the drawing:

Fig. 1 is a plan view of a tendon protector or similar article in a spread-out condition, showing our new design; and

Fig. 2 is a rear elevational view of the same with the sides slightly curved, as it would appear when in use, and attached to a skate shoe,

shown in dotted lines for illustrative purposes only, the tieing cord shown in Fig. 1 being omitted for convenience of illustration.

We claim:

The ornamental design for a tendon protector or similar article, as shown and described.

GEORGE OWEN, JR.
JEROME A. RUBICO.
